(57) **CLAIM**

The ornamental design for a serving tray with bicycle bell, as shown and described.

DESCRIPTION

FIG. 1 is a top plan view of a serving tray with bicycle bell showing my new design;

FIG. 2 is a bottom plan view thereof;

FIG. 3 is a right side elevation view thereof;

FIG. 4 is a left side elevation view thereof;

FIG. 5 is a front elevation view thereof;

FIG. 6 is a rear elevation view thereof; and,

FIG. 7 is an isometric view thereof.

The broken lines in FIG. 7 of the drawings depict a beverage glass as environmental subject matter only and form no part of the claimed design.
